John H. Bellamy's Design for a Clock Front

4299

PATENTED AUG 23 1870

*M. A. Powers
Duncan Bradford
Wm. C. DeCoste*

*Inventor,
John H. Bellamy*

United States Patent Office.

JOHN H. BELLAMY, OF CHARLESTOWN, MASSACHUSETTS.

Design No. 4,299, dated August 23, 1870.

DESIGN FOR CLOCK-FRONT.

The Schedule referred to in these Letters Patent and making part of the same.

To all whom it may concern:

Be it known that I, JOHN H. BELLAMY, of Charlestown, in the county of Middlesex and State of Massachusetts, have invented and produced a new and original Design for a Clock-Front, of which the following is a full, clear, and exact description, reference being had to the accompanying photograph making part of this specification.

This invention consists in a clock-front, having emblems and scroll-work arranged and grouped together so as to produce an ornamental and unique open-work design.

In the photograph---

A represents a ring or circular frame, for the dial of the clock.

The dial-frame A rests upon legs or supports, L L', of ornamental scroll-work, the right leg, L, inclosing within its scroll a square, M, and the left leg, L', inclosing a plumb, J.

Between the two supports, L L', is placed a level, C.

On the right-hand side of the dial-frame A is a ladder, O, having three rounds, and on the left are two parallels, I J, inclosing a book, G, and a circle, H.

Above the dial-frame A is a square, B, and a compass, C, inclosing a problem, D.

On the right-hand side of the square is a gavel, P, and on the left-hand side a rule, F, the whole being inclosed, or nearly so, in ornamental scroll-work.

Claim.

What I claim as my invention, and desire to secure by Letters Patent, is—

The design for a clock-front, herein shown and described.

Witness my hand this 11th day of July, A. D. 1870.

JOHN H. BELLAMY.
